R. E. REARDON

TOY PISTOL

Filed July 2, 1923

Fig. 1.

Inventor:

Robert Edwin Reardon

UNITED STATES PATENT OFFICE.

ROBERT EDWIN REARDON, OF COLUMBIA, PENNSYLVANIA, ASSIGNOR TO VICTORY SPARKLER & SPECIALTY COMPANY, OF ELKTON, MARYLAND, A CORPORATION OF DELAWARE.

TOY PISTOL.

Application filed July 2, 1923. Serial No. 648,926.

To all whom it may concern:

Be it known that I, ROBERT EDWIN REARDON, a subject of the King of Great Britain, residing in the town of Columbia, county of 5 Lancaster, and State of Pennsylvania, United States of America, have invented a new and useful Toy Pistol, of which the following is a specification.

My invention relates to improvements in 10 toy firearms, especially of the tape fed, repeating pistol type.

My object is to provide a novel, simple, easily assembled, readily loaded and positively operating toy pistol or gun. I accomplish this as follows, developing from the cap strip feeding mechanism of my allowed patent application bearing Serial No. 15 549,944, and incorporating a number of novel and useful features of construction 20 that are of operative and commercial value in this art. Especially I make the cap feed path a clearway, by having the hammer normally retracted from the anvil. In the usual construction of toy pistols of trigger pressure operated, tape fed type, the hammer normally bears on the anvil and must be raised therefrom coincidently with the advance of the cap tape, thus necessitating nicety of adjustment of working parts and 25 also conducing to feed obstruction from sticking of tape to hammer or anvil face through continued compression. In my device the hammer contacts with the anvil only momentarily, while striking an explosive cap thereon, and retracts as the feed means retracts. I also provide a novel form 30 of loading door or wall opening in the pistol casing, which is readily assembled, facilitates loading and cleaning by opening a large area, and is an effective closure, even 35 without friction or spring locking. I further provide in the cap feeding means a self-adjusting shield against back fire from the exploding cap; furnish finger pressure 40 means for controlling and applying striking force to the hammer; retract the trigger member, retract the hammer and furnish striking force to the hammer by means of a single spring, very easily assembled; and 45 provide a pistol body or casing that may conveniently be assembled by a single screw, that is hidden when the casing is closed, thus allowing the pistol exterior to be molded in 50 more exact semblance of a real pistol.

I attain these objects by the mechanism 55 illustrated in the accompanying drawing in which:

Figure 1 is a side elevation of my toy pistol, with door plate opened, showing in full and dotted line the working parts in 60 normal position therein and a roll of cap tape in place.

Figure 2 is a side elevation of the left side of the casing of my toy pistol, showing in place thereon as assembled, in normal position, the working parts in somewhat modified form of construction.

The body or casing of my toy pistol is preferably made in three parts, the sides A and B, left and right respectively, and the 70 right side door plate C, pivoted between the sides A and B by means of an apertured flange C¹ on door plate C fitting on a ridge-based pin A¹ that projects from side A at right angle thereto. The said flange C¹ of 75 door plate C is tapered from its pivotal aperture C² to its edge C³, both radially from its pivotal point and upwardly along its rearward margin, so that when the said door plate C is in normal closed position it 80 is held there snugly by the tapering flange C¹ being rotarily wedged marginally between the adjoining pistol sides A and B. When moved from such normal closed position the flange C¹ of door plate C immediately loosens on its pivot A¹, on which it is loosely fitted, and the door plate C may be released outwardly from its jamb and swung upwardly until it comes to rest, clear of the 85 pistol side opening.

A trigger member D is pivoted by transverse pin or preferably hubs, as D¹, between the casing sides A and B, by means of holes, as B¹, in said sides. It bears a tape guiding wall D² having a concave side D³ with a 90 step or platform D⁴ therein, an upward extension or nose D⁵ of said wall above said step D⁴, and a rearward enlargement or hump D⁶ at the lower end of said wall. Bridging the concave side D³ of said tape 95 guiding wall D², extending from the rearward hump D⁶ at the lower end of said wall, which hump D⁶ it embraces, to the step D⁴ which it overlaps, is a resilient liner or bridge E, preferably of flat spring formed 100 to snap on the hump D⁶ and hold its position by engagement therewith. A spring pawl F mounted and having limited vertical

movement in an open sectored cylindrical socket D^7 , projected at right angles from the trigger member D base, bears with its free end upon the liner E at the point where the said liner overlaps and rests upon the step D^4 in tape guiding wall D^2 . A U-shaped pawl spring G embraces in the open-sectored cylindrical socket D^7 the parti-cylindrical or headed pivotal end of spring pawl F and, by expansion against the upper side of the pawl F and the opposite edge of the open sector in cylindrical socket D^7 , normally presses the pawl F against the liner E on step D^4 of tape wall D^2 . From the upper side of the pawl F , which may be called a grip pawl, and adjacent its free end there extends upwardly a flange F^1 , approximately paralleling and extending slightly beyond the upward extension or nose D^5 of the tape guiding wall D^2 . From the pivotal end of the said pawl F , limiting its pivotal movement by lying in a recess D^8 in the wall of cylindrical socket D^7 , and also holding said pawl in said socket by riding underneath the frame of casing side B of the pistol, there adjacent, extends longitudinally of the pawl a tail F^2 .

On the inward side of the frame of casing side B , at B^3 , diagonally adjacent the normal position of tape guiding wall D^2 of trigger member D , is projected at right angle an open sectioned cylinder in which is mounted by means of a circularly formed end a spring pawl K , preferably made of suitably shaped flat spring material, which may be called a check or stop pawl. This spring pawl K bears with its free end upon the liner E of tape wall D^2 of trigger member D , normally bearing upon the said liner where it rests upon the step D^4 , interposed between said liner and the free end of grip pawl F . On casing side A of the pistol, opposite the cylindrical socket B^3 of stop pawl K , projected from casing side B thereat, is a boss or raised platform A^4 with a slightly higher ledge A^5 on its upper margin, adapted to keep in its socket the circularly formed end of pawl spring K and prevent friction of the lower edge of same upon trigger member D . Centrally of the boss A^4 is a threaded hole A^6 for the end of pistol assembling screw.

Radiating from the pivotal point or hub D^9 of the trigger member D , upwardly, forwardly and downwardly respectively, are: an upward extension or arm terminating in a top flanged stud D^{10} which projects at right angle parallel with hub D^9 ; a hammer engaging nose extension D^{11} ; and a finger extension or trigger proper, D^{12} .

Mounted on the hub D^9 of the trigger member D is a coiled spring S having three arms, in this mode of construction made by coiling a doubled wire, thus having a double arm and two single arms. The double or

loop arm S^1 of the spring S lies against the rearward side of the finger extension D^{12} of trigger member D , looping over a fin D^{13} on same. The upper arm S^2 of the spring S lies against the under side of the top flanged stud D^{10} and projects rearwardly therefrom. The third arm, S^3 , of the spring S lies against the forward side of a stud A^2 on the casing side A , located, in this construction, in the pistol grip, adjoining the boss A^4 . The spring S is thus held assembled to trigger member D by its tension centrally on hub D^9 and the pressure of arms S^1 and S^2 against finger extension D^{12} and top flanged stud D^{10} , respectively. It may be assembled to the trigger very readily and the spring and trigger handled as one in further assembly. The upper or second arm S^2 of the spring S projects beyond the retaining and restraining flanged stud D^{10} to sufficient distance to engage the head H^1 of a hammer H , by means of a downward flange extension H^2 from said hammer head H^1 which has a side notch or recess H^3 therein in which lies the extended arm S^2 of spring S and through which said arm S^2 passes, controlling by such engagement the position of hammer head H^1 and normally holding same retracted from the anvil A^3 , which is a flange extending at right angle from the upper margin of casing side A , subjacent the marginal wall of said casing.

The hammer H is transversely pivoted between the casing sides A and B of the pistol, preferably by means of nubs, as H^4 , on the hammer and holes, as B^4 , in the said casing sides, and adapted to percuss with head H^1 upon the anvil A^3 . A downward H^5 extension of the hammer H , below the pivotal point H^4 of same, has a transverse recess H^6 therein, cylindrical in shape and having an open sector on the side facing the trigger member D . In the said transverse recess H^6 and having limited vertical movement in the open side of same, through which it projects, is mounted, by means of an enlarged, parti-cylindrical head, an upwardly resilient strut I . A U-shaped strut spring J embraces in the cylindrical recess H^6 the parti-cylindrical head of the strut I , and by compression against its upper side and the adjacent edge of the open sector of said cylindrical recess H^6 keeps the strut I normally depressed.

The working parts of my pistol being in place and the casing parts adjusted, assembly is completed by insertion of an assembling screw L , through the frame of casing side B at B^3 , the inwardly projected cylindrical socket of pawl spring K thereat, and the cylindrically formed butt of said pawl spring K mounted in said socket, into the threaded hole A^6 in the boss A^4 . The head of said assembly screw L is flat and countersunk. The screw engaging hole A^6

need not extend completely through casing side A, as the boss A⁴ may be made high enough centrally to take all the threading necessary to substantial engagement of assembly screw L therewith. It will be obvious that door plate C when closed rides over the frame of casing side B at B³ and covers the head of assembly screw L. The screw point not extending through casing side A, the means of holding the pistol together is thus invisible when pistol is closed, and any means of assemblage may be indicated in the molded exterior of the pistol without contradictory appearance of the real means or marring the exterior design.

A roll of cap tape M is shown in place in the pistol, in Figure 1, mounted on a post A⁷, located, in this construction, in the grip section of the pistol. For descriptive convenience the three leading caps are designated as M¹, M² and M³.

The modified form of the working parts of my toy pistol, shown in Figure 2, differs from the preferred form shown in Figure 1 and described in the foregoing, in substituting for the combination of hammer H and upwardly resilient strut I a hammer H of which the pivot nubs, as H⁴, instead of being mounted in circular holes, as B⁴, in the casing sides A and B, are mounted in diagonally upward slots, as A⁸, inclining forward, that are extended from the location of said pivot holes, as B⁴, of Figure 1 construction. The hammer nubs, as H⁴, normally lie in the lower end of the diagonal slots, A⁸, and are held there by pressure on the pivotal end of the hammer H exercised by a fourth arm S⁴ of spring S, formed by doubling the arm S² of same at its terminus and returning it through hammer head notch H⁸ in tangential forward extension towards the hammer pivotal point, beneath which, in the hammer downward extension H⁵, it engages in and presses downward on the lower side of a recess H⁷. An integral right angular marginal extension H⁸ of rearward side of the downward extension H⁵ of hammer H, takes the place of the strut I of Figure 1 in engaging with the nose D¹¹ of the trigger member D, the latter escaping therefrom in return to normal position by raising the hammer pivotal end bodily, the nubs H⁴ riding upward in diagonal slots A⁸, until the rotation of the trigger member D and the recession of hammer H as its nubs H⁴ rise in the forwardly inclined slots A⁸, terminates their engagement.

The operation of my toy pistol is effected as follows: A roll of explosive cap tape, as M, is mounted on post A⁷ on casing side A and the free end of the tape passed up along the tape guiding wall D² of trigger member D, along the resilient liner E of said guide wall D², under the free ends of spring

stop pawl K and spring grip pawl F, until a cap hummock, preferably the second leading cap, as M², is slightly in advance of the nose of stop pawl K, on which the free end of grip pawl F normally rides. The door plate C of the pistol is then closed. The trigger extension D¹² is then pressed, thereby rotating the trigger member D and raising the tape guiding wall D² with pawl F gripping the tape M against same by engaging a cap hummock, as M², and pawl K riding over the lower cap hummock, as M³, as the guide wall D² and tape M rise, until the upper flange F¹ of pawl F bears the leading end of cap tape M against the threshold of the overhead anvil A³, placing the foremost cap, as M¹, directly opposite said anvil. Simultaneously with this action the nose D¹¹ of the trigger member D rotates downwardly upon the strut I extending from the pivotal end of the hammer H, thereby tending to retract still farther from anvil A³ the hammer head H¹, against which at the same time the projected second arm S² of operating spring S, by engagement in notch H³ of hammer head flange H², bears with increasing pressure, continuing until the downward rotation of trigger member nose D¹¹ and hammer strut I, at the instant of arrival of cap M¹ in striking position on anvil A³, releases the hammer H to strike the anvil and cap thereon.

Pressure upon the trigger being removed, it returns to normal position by pressure of third arm S³ of the spring S, upon the stud A² of casing side A of the pistol and pressure of arm S⁴ of said spring upon the rear of trigger extension D¹², the upwardly resilient hammer strut I permitting the return of nose D¹¹ of the trigger member D. As the trigger member D returns to normal position, the tape guiding wall D² descends, passing along the back of the cap tape, M, and the spring grip pawl F rides down the face of said tape, over the next cap hummock thereon, onto the free end or nose of spring stop pawl K, which, by pressing against the guide wall D², the tape M, engages said tape body or a cap hummock thereon and prevents the said tape from receding with the guide wall D². The resilient liner E which bridges the major portion of the path of the free end of stop pawl K, practically ensures engagement of the pawl K with a cap hummock at each advance, thus positively regulating the tape feed, and determining the extent of each step by the distance between the successive cap hummocks.

The parts having returned to normal position, another pressure of the operator's finger on the trigger repeats the action, which may thus be continued until each successive cap has been fed forward and detonated.

Operation of the modified form of my toy pistol shown in Figure 2 is similar, differing in the action only in the detail of trigger nose D¹¹ in return to normal position 5 escaping from the strut replacing extension H⁸ of hammer H by elevating the pivotal end of said hammer H, by the nubs H⁴ of same riding up in the diagonal pivotal slots, A⁸, in which slots the pivot nubs H⁴ are 10 normally depressed by the reverse extension S⁴ of arm S² of the operating spring S.

It will be understood that a number of modifications in and deviations from my invention as herein presented, may be made 15 without departing from the spirit thereof.

I claim:

1. In a toy firearm, an anvil, a hammer, a trigger, and single spring means for holding the hammer normally retracted from the 20 anvil, returning the trigger to normal position, and applying striking force to the hammer.
2. In a toy firearm, an anvil, a hammer, a trigger, and single triple armed spring 25 means for retracting said hammer and trigger and percussing said hammer upon the anvil.
3. In a toy firearm, an anvil, a hammer, a trigger, and single operating spring means 30 for retracting said hammer and trigger, maintaining their relation to each other, and percussing the said hammer upon the said anvil.
4. In a toy firearm, a hammer, an anvil, a trigger member carrying means for carrying 35 detonating material to said anvil and means for maintaining a constant controlling connection with the hammer and maintaining itself in normal position.
- 40 5. In a toy firearm, an anvil, a hammer, a trigger member having means for gripping and advancing to the anvil the free end of an explosive cap tape and means for adher-

ently mounting an operating spring and limiting its action with relation to the hammer, 45 an operating spring mounted adherently on the said trigger member and having operative bearing upon the hammer for retraction from anvil or advancement thereto and thus 50 operating to maintain said trigger member in normal position and said hammer normally retracted from the anvil.

6. In a toy pistol, a casing comprising two sides joined longitudinally and having a 55 ridge based post projected right angularly interiorly from one side, and a side door plate hinged transversely between the said casing sides by means of an apertured, offset flange tapered radially from said aperture and marginally upward, adapted to fit 60 loosely on said ridge based interior post and wedge between the adjoining casing sides as the door plate rotarily assumes closed position and is thereby drawn into its engaging recess on the casing side, of which it forms 65 the completing section.

7. In a toy firearm, an anvil, a trigger member adapted to bear explosive cap tape to said anvil and by means of a resilient shield press said cap tape against the 70 threshold of said anvil.

8. In a toy pistol having a casing comprised of three parts, means for assembling same consisting of one interiorly located, 75 normally hidden assembly screw.

9. In a toy firearm, an anvil, and a trigger member adapted to carry explosive cap tape to said anvil, said trigger member bearing a resiliently faced tape guideway thereon.

80 10. In a toy firearm, an anvil, a trigger member, a tape pathway on said trigger member, a recess in said tape pathway, and a spring bridging said recess.

ROBERT EDWIN REARDON.
